Primary Examiner — Rosemary K Tarcza*Assistant Examiner* — Nathaniel D Buckner(74) *Attorney, Agent, or Firm* — Schwabe Williamson & Wyatt, P.C.(57) **CLAIM**

We claim the ornamental design for a housing for log splitter, as shown and described.

DESCRIPTION

FIG. 1 is a perspective view of a housing for log splitter;
FIG. 2 is a front view thereof;
FIG. 3 is a back view thereof;
FIG. 4 is a left side view thereof;
FIG. 5 is a right side view thereof;
FIG. 6 is a top view thereof;
FIG. 7 is a bottom view thereof; and,
FIG. 8 is a front perspective view of the housing for log splitter in a position of use on a log splitter.
The dashed lines are included for illustrating environmental structure and form no part of the claimed design.
